ATTORNEY

UNITED STATES PATENT OFFICE

JACOB T. UDEN, OF NEW YORK, N. Y.

SHOE SHINING MACHINE

Application filed December 19, 1932. Serial No. 647,841.

My invention relates to shoe shining machines and has particular reference to motor operated machines for shining or polishing shoes on the wearer's feet.

5 The object of my invention is to provide an automatic machine for shining or polishing shoes after they have been covered or sprayed with shoe polishing liquid (such, for instance, as are described in my applications Serial
 10 Nos. 640,398, filed Oct. 31, 1932, and 648,415, filed Dec. 22, 1932). For this purpose I use an endless belt with bristles inside forming a flexible brush, similar to the one described in my Patent No. 1,881,036. Another object of
 15 my invention is to provide a means for cleaning the brush by vacuum from a suction blower operated by the same motor which operates the endless belt-brush. Still another object of my invention is to provide means for preventing the shoe to be placed inside of the brush for polishing until the device is electrically unlocked. I also provide a convenient platform on which are assembled the shoe shining belt, spraying machine, cone-shaped
 20 brush for polishing the toe portion, suction blower, and electric motor with transmission for driving all these various apparatus.

25 My invention is more fully described in the accompanying specification and drawing in
 30 which—

Fig. 1 is a section elevation of my machine in an inoperative position, Fig. 2 is the same in an operative position, Fig. 3 is a plan view of the same assembled on a platform with
 35 other devices, Fig. 4 is an end view partly in section, and Fig. 5 is a side view of the platform with my machine.

30 My shoe shining machine consists of a belt 1 mounted on rollers 2 and 3. This endless belt has long and stiff bristles 4 in its upper portion, the lower portion being smooth so that it can engage the rollers 2 and 3, these rollers being of such height that they just reach the bristled or brush portion of the belt.
 40 The roller 3 is mounted on a shaft 5 fastened in a rectangular block 6 which slides between guiding bars 7 mounted on a base 8. The bars 7 are connected together with a wall
 45 9 forming a partly open box. A screw 10 is
 50 threaded in the wall 9 and rests against a

pressure plate 11. A spring 12 is placed between the block 6 and the plate 11. The spring 12 tends to keep the belt 1 under tension, which can be further adjusted by the screw 10. A pulley 13 is mounted on the roller 3 and turns with it on the shaft 5. A twisted belt 14 connects the pulley or sheave 13 with a pulley 15 on a transmission shaft 16. The latter is driven by an electric motor 17 through pulleys 18 and 19 with a belt 20.

55 The other roller 2 rotates on a hollow shaft 21 mounted in a block 22 fastened to the base 8. The rollers 2 and 3 have curved or cambered surface in order to keep the belt 1 from sliding off, and have flanges 23 against which rests the lower edge of the belt 1.

50 A platform for a shoe 25 is placed inside of the belt 1. This platform 24 is mounted on a hollow cylinder 26 which slides in a tube 27 mounted on the base 8. A spring 28 tends to keep the platform in its raised or inoperative position as shown in Fig. 1. A screw or pin 29 fastened to the tube 26 and sliding in a slot in the tube 27 limits the upward movement of the platform under action of the spring. Tension of the spring 28 is such that it becomes compressed under the weight of the foot placed on the platform 24 bringing the latter to the operative position shown with dotted lines in Fig. 1. A metal housing 30
 60 encloses the belt 1 and the rollers 2 and 3.

65 The housing 30 represents a protective cover for the belt 1 and has a flange 31 on top extending inside beyond the edge of the belt but not reaching the space defined by the end of the belt bristles. A ring 32 made of some flexible material, such as rubber, is attached to the flange 31. Its central aperture is narrower than the shoe so that the latter causes the ring to deflect when placed in the operative position. This ring affords a certain protection to the foot against the dust which may escape from the belt. The flange 31 also prevents the belt 1 from being pulled off its rollers 2 and 3. The housing is inserted in its place through a corresponding hole in a raised platform 33 and is fastened with hooks or clips 34.

70 A short tube 35 is attached to the rear end of the foot board 24 and slides in the tubular
 75 80 85 90 95 100

shaft 21, forming an additional guide for the foot board 24. The tube 35 is closed on top but is provided with a number of apertures 36 directed against the bristles 4. 5 A pipe 37 is fitted in the tubular shaft 21 at the bottom, at a point below the end of the tube 35 when the foot board is fully depressed. This pipe 37 extends to the intake side of a suction blower 38 driven from the 10 shaft 16 by a belt 38' with pulleys 39 and 40. The exhausted dust is collected in a dust box 41.

A separate brush 42 is provided for shining the toe portion of the shoe. This brush 15 has a bell-shaped opening in front with long, stiff bristles. It is mounted on a shaft 43 rotating in bearing brackets 44 and has a pulley or sheave 44' connected by a belt 45 with a pulley 46 on the shaft 16.

20 A shoe spraying machine 54, preferably of a type described in my above mentioned patent, is located at the left of the bell-shaped brush 42. The raised platform 33 surrounds the brushing machines and the spraying box, 25 and is provided with rubber pads 55 for the user's feet. A step 56 leads to the platform from the front, and railings 57 at the sides afford a means for the user to steady himself while he inserts his feet in the shining 30 devices.

A switch (not shown) for starting and stopping the motor 17 may be placed on the wall within reach of the user, or on one of the rail bars 57. Instead of an ordinary switch, 35 a coin-operated circuit closing device may be used with a clock attachment for limiting the time of motor operation. This device is not shown as I propose to use one of the standard devices used for such purpose.

40 The whole assembly may be enclosed in a cabinet with a door under lock, the latter being arranged to open upon insertion of a suitable coin, starting at the same time the operation of the time switch. This arrangement also is not shown, as it may be of any suitable construction.

The operation of my machine is as follows.

The user starts the motor 17 and places 50 one of his feet in the polish spraying machine 54, while resting with the other foot on one of the pads 55 around the machine. After the polish has been applied, the foot is transferred into the box 30 and placed on the foot board 24, depressing it until it stops 55 against the shafts 5 and 21. The shoe will then be polished or shined by the rapidly moving bristles of the belt-brush 1. The upper portion of the foot will be protected from dust by the rubber shield 32. At the same 60 time the dust will be sucked off through the upper hole 36 in the tube 35 and through the pipe 37 into the suction blower 38, to be deposited in the dust box 41. The belt will polish the shoe on all sides, but in order to 65 polish the instep portion of the shoe, the foot

is placed on the board 48' against the bristles of the bell-shaped brush 42.

In order to prevent the board 24 to be depressed when the motor is not working, a latch 59 is pivotally mounted on the wall of the tube 27 extending inside so as to prevent the tube 26 from moving all the way down. A magnet 60 is placed at the other side of the latch so as to pull it out when this magnet is energized. The magnet coil is connected in series with the motor and becomes operative when the latter is running.

As is shown on the drawing, a single motor operates all the devices necessary for the performance of the shining operations. It is 80 evident that the method of transmitting the power may vary without departing from the spirit of my invention. Chains may be used, for instance, instead of belts, with sprockets instead of pulleys or sheaves. Gears may be 85 also used if preferred, and any skilled mechanic may arrange them in accordance with the general scheme indicated on the drawing.

The suction blower may be of any suitable design, and it may be provided with additional outlets for a portable pipe with a clothes cleaning nozzle, or with a brush with vacuum nozzle. These devices are not shown as they may be readily arranged by anyone 90 skilled in the art.

I claim as my invention:

1. In a shoe shining machine, the combination with an endless belt, of rollers supporting said belt in a vertical position and engaging its lower portion, bristles on the inside of said belt above said rollers, a foot board inside of said belt, a housing around said belt adapted to prevent said belt from being moved off said rollers, and an elastic plate on top of said housing adapted to cover said bristles and provided with an aperture for the shoe to be shined.

2. In a shoe shining machine, the combination with an endless belt, of rollers supporting said belt and engaging the lower portion of said belt, bristles on said belt forming a flexible brush above said rollers, a footboard inside of said belt for a shoe, means to support said footboard in an inoperative position above said bristles, said supporting means adapted to yield under pressure from a foot with said shoe so as to bring said footboard with said shoe in an operative position inside of said belt, a hollow shaft for one of said rollers, a tube slidably fitted in said hollow shaft and attached to said footboard, said tube being provided with apertures directed against said bristles, and means to exhaust air from said tube.

3. In a shoe shining machine, the combination with an endless belt, of rollers supporting said belt, bristles on the inside of said belt forming a brush, means to rotate said rollers thereby moving said belt, a footboard yielding supported inside of said belt and adapt-

ed to be lowered into an operative position by the pressure of a foot with a shoe, a pipe movably supported inside of said belt and connected with said footboard, means to raise 5 said footboard with said pipe when said shoe is removed, said pipe being provided with apertures directed against said bristles, and means to create suction in said pipe and through said apertures.

10 4. In a shoe shining machine, the combination with an endless belt, of rollers supporting the lower portion of said belt, brush-forming bristles on the inside of said belt

above said rollers, means to rotate said rollers thereby moving said belt, a footboard movably supported inside of said belt in an inoperative position above said bristles, said footboard being adapted to be lowered into its operative position by the pressure of a foot with a shoe, and means for cleaning said bristles when said footboard is raised into its inoperative position, said cleaning means being movably connected with said footboard. 75

In testimony whereof, I affix my signature.
JACOB T. UDEN.
